United States Patent Office

Des. 208,923
Patented Oct. 17, 1967

208,923

COMBINED SCOREBOARD AND ADVERTISING SIGN

Gustave F. Falkenberg, Brookfield, Wis., assignor to Dimensional Products, Inc., Milwaukee, Wis., a corporation of Wisconsin

Filed Apr. 18, 1966, Ser. No. 1,909

Term of patent 14 years

(Cl. D34—5)

Fig. 1

Fig. 2

FIG. 1 is a view in perspective of a combined scoreboard and advertising sign showing my new design,
FIG. 2 is a top view thereof,

FIG. 3 is a front view in elevation thereof, and

FIG. 4 is a view in cross section thereof through the plane 4-4 shown in FIG. 3.

I claim:

The ornamental design for a combined scoreboard and advertising sign, as shown.
